UNITED STATES PATENT OFFICE

134,662

DESIGN FOR A DINING BOOTH UNIT

Frank Mastrangelo, Fitchburg, Mass.

Application January 14, 1942, Serial No. 105,202

Term of patent 3½ years

To all whom it may concern:

Be it known that I, Frank Mastrangelo, a citizen of the United States residing at Fitchburg, in the county of Worcester and State of Massachusetts, have invented a new, original, and ornamental Design for a Dining Booth Unit, of which the following is a specification, reference being had to the accompanying drawings, forming part thereof.

Fig. 1 is a perspective view of a dining booth unit, showing my new design; and

Fig. 2 is a top plan view thereof.

The dominant feature of my design resides in the portions shown in full lines.

I claim:

The ornamental design for a dining booth unit, as shown and described.

FRANK MASTRANGELO.
